UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING-MACHINE.

1,340,469.

Specification of Letters Patent. Patented May 18, 1920.

Application filed November 1, 1917. Serial No. 199,722.

To all whom it may concern:

Be it known that I, JOHN WALDHEIM, a citizen of the United States, residing in Elizabeth, in the county of Union and State of New Jersey, have invented certain new and useful Improvements in Typewriting-Machines, of which the following is a specification.

My invention relates mainly to typewriting machines in which usually two sets of type-bars are used.

Heretofore the sets have been arranged side by side, and the platen carriage has been movable from one type-set to the other. In such machines, it is necessary, at each such shift of the platen, to re-position the same by means of the usual scale and pointer, each type-set usually having a separate scale. Moreover, there has been the necessity of making special margin-gage, line-locking and other mechanisms, owing to the fact of the carriage making these excursions from one type-set to the other.

One object of the present invention, which is illustrated in connection with features disclosed in my co-pending application, Serial No. 196,797, filed October 16, 1917, is to simplify the operation of the machine, by making it unnecessary to re-position the carriage when making the necessary excursion from one type-set to another. Another object is always to preserve,—in this class of machines, the same relation between the carriage and the keyboard, thus reducing to a minimum the inconvenience to the operator.

These and other objects may be attained by arranging the type-sets one back of another, and mounting the platen so that it may be moved from front to back of the machine into effective relation with either type-set. I preferably mount the platen on a secondary carriage, which is slidably supported on a primary carriage, the latter controlled by an escapement mechanism. The two carriages travel together in letter-feed direction, but the secondary carriage may be moved at right angles to this path of travel, to enable the platen to coöperate with either type-set.

As an additional feature, I have provided means for connecting a single set of keys to either type-set. Each type-set has associated therewith a set of intermediate levers.

With these sets of intermediate levers there

is associated a single set of sub-levers, which may be differently actuated, by the keys, to coöperate with either set of intermediate levers. The key-levers are connected to the sub-levers by links which may be shifted in slots in the sub-levers, so as to change the points of connection thereof, with the sub-levers.

The connecting links are preferably automatically controlled by the secondary or platen carriage.

Since a single main carriage is employed, a single letter-feeding escapement may be used, for the two type-sets, which may be actuated by either one of two universal bars, one for each type-set.

The case-shift mechanism preferably comprises two connected swinging frames, and a key that may operate them. The platen may be shifted from lower to upper-case by the same key, when it is in effective relation with either type-set.

A single inking ribbon is preferably used, which is moved from one type-set to another with the platen. I preferably employ for this purpose a carriage-carried ribbon, of the type shown in the patent to H. S. McCormack, No. 972,706. The ribbon may be fed by the platen line-spacing mechanism, comprising an operating handle which is preferably supported on the secondary carriage.

Two type-guides are provided, one for each set of type-bars. The type-guide associated with the rear set of type-bars is pivotally mounted, so that it may be swung out of the way when the platen is moved from the rear to the front set of type-bars. This swinging is preferably done by a spring under the control of the typewriter carriage. When the platen is moved from the front to the rear type-set, the pivoted type-guide remains in its lowered position until the latter part of said movement, and then rises, since the secondary carriage becomes effective, after the platen has passed over the type-guide, to throw the latter up to working position.

I have illustrated the invention in connection with an Underwood, but it may readily be employed with other typewriting machines.

Some of the features may also be used in machines in which two keyboards are provided. Also in other machines in which

there is provided a plurality of sets of type-bars which may be actuated by a single set of keys.

Other features and advantages will hereinafter appear.

Figure 1 is a top plan view of the machine, showing the two sets of type-bars, one in back of the other, and the platen which may be moved in a direction from front to back of the machine to bring it into effective relation with either set of type-bars.

Fig. 2 is a sectional side view, taken substantially on the line 2—2 of Fig. 1, and looking in the direction of the arrows on said line.

Fig. 3 is a sectional front view with some of the parts omitted, taken on the line 3—3 of Fig. 2, and looking in the direction of the arrows on said line.

Fig. 4 is a view of some of the parts in Fig. 2, showing a key depressed, and the sub-lever effective with one of the front sets of type-bars. This figure also shows how one end of the sub-lever moves idly away from the intermediate lever associated therewith.

Fig. 5 is a side view, partly in section, showing the platen moved into effective relation with the rear set of type-bars, and the connections from the key-levers changed, so that the latter, when depressed, will actuate the rear set of type-bars. The platen is also shown in effective relation with the rear shift-frame and the type-guide swung to its effective position.

Fig. 6 shows a type-bar of each set with different kinds of type thereon.

Each character key 10, when depressed, moves a key-lever 11, which operates a link 12 to swing a sub-lever 13 about its fulcrum 13^a. The forward end 14 of sub-lever 13 engages with a stud 15, to swing a bell-crank or intermediate lever 16 about a fulcrum 17, thereby swinging a type-bar 18 about its fulcrum 19 to cause either lower-case type 20 or upper-case type 21 to strike against the front side of a rotatable platen 22.

In Figs. 1 and 2, it will be seen that there are two type-sets, each comprising type-bars 18, arranged one in back of the other. The platen 22 may be transferred from the full-line position, where it co-operates with the front type-bar set, to the dot-and-dash line position, shown in Fig. 2, to render it effective with the rear type-set. When the platen is thus moved, the points of connection of the several links 12 with the sub-levers 13 are also changed, to enable them to operate the other set of type-bars, in a manner which will presently be described. For this purpose, while changing the connections, the links 12 are swung about their pivots 25 on the key-levers 11, to move headed studs 26, projecting laterally from the links 12, from the forward ends of slots

27 to the rear ends thereof, as shown in Fig. 5.

If, after transferring the platen to the rear set, any key-lever 11 is depressed, its sub-lever 13 is actuated in a direction opposite to that of Fig. 4. Thus, the rear end 28 of the sub-lever will actuate the rear bell-crank or intermediate lever to swing the type-bar about its fulcrum, and cause the rear types to swing against the front side 75 of the platen. At this time the forward end 14 of the sub-lever 13 moves idly away from the associated stud 15.

It will be understood that the link-and-sub-lever arrangement actuated by the key 80 11 may be advantageously used in other kinds of typewriting machines. The two type-bars associated with the same sub-lever 13 may bear the same characters, but of different characteristics, and either type-bar 85 11 may be actuated by a single key-lever by changing the point of connection between the key-lever 11 and the sub-lever 13 by connecting the link 12 at either side of the sub-lever fulcrum 13^a, so that the sub-lever 13 90 may be moved in either clockwise or counter-clockwise direction.

By arranging the type-bars one set back of the other, it will be seen that each key-lever 11, its associated link 12, the sub-lever 95 13, and the two intermediate levers or bell-cranks 16, associated therewith, may lie substantially in the same plane, thus avoiding twisting action and side strain between the key-lever and the intermediate lever 16. 100

Letter-feeding movements of the platen are controlled by a suitable escapement comprising a pinion 30. The pinion 30 has meshing therewith a rack 31, pivotally supported at 32 on a primary carriage 33. The primary carriage 33 travels on front and rear rails 33^a and 33^b, respectively, and has supported thereon a secondary carriage or truck 34, which may be provided with grooved rails 35, secured thereto, one at 110 each end, engaging with suitable rollers 35^a on the primary carriage. This permits the secondary carriage to be moved at right angles to the direction of travel of the primary carriage to bring the platen 22 carried by 115 the secondary carriage into effective relation with either type-set. The escapement pinion 30 is connected to an escapement wheel 36, by the usual one-way acting pawls (not shown), to transfer rotative movement to 120 the escapement wheel. A spring drum 37 is effective to move the platen in a letter-feed direction and is connected to the primary carriage 33, by a strap 38.

The letter-feed movements of the platen 125 22 and the carriage 33 may be effected by either set of type-bars. Each set of type-bars has a universal bar 39 associated therewith, actuated by heels 40 on the type-bars 18. The universal bars 39 form part of a 130

floating frame 41, which, when actuated, rocks a dog rocker 42 rearwardly to disengage a loose dog 43 from the teeth of the escapement wheel 36 and bring a fixed dog 44 into the path thereof. A suitable spring (not shown) returns the dog rocker and the floating frame to their normal positions. Thus, the dog rocker, by means of the floating frame 41 and the return spring 29, is 10 rocked to vibrate the loose and fixed dogs 43 and 44, respectively, between the teeth of the escapement wheel, to effect the letter-feed movement of the carriage 33, which is constantly under the influence of the spring 15 drum 37.

From the foregoing, it will be understood that the secondary carriage moves with the primary carriage during letter-feeding movements; that the secondary carriage may 20 be returned to the first position on a printing line without disturbing its position relative to the primary carriage, and that the secondary carriage may be shifted from one type-set to another without disturbing the 25 escapement mechanism or the position of the primary carriage; thus, the primary carriage travels in the same zone irrespective of the position of the platen relative to the type-sets.

30 The change of connections of the links 12 and sub-levers 13 may be effected when the platen 22 is moved from the front to the back of the machine, or, in other words, when the platen is moved from one type-set 35 to another. This may be controlled by a cross-bar or rail 45 secured to the rear of the secondary carriage 34, which, during the latter part of the rearward movement of said carriage, engages with the roller 46 40 mounted at the upper end of a lever 47 to rock a shaft 48 to which the lever 47 is secured. The lever 47 is preferably located near the center of the machine (Fig. 1), and is secured to one end of the rock shaft 48. 45 The rock shaft 48 is supported by a U-shaped bracket 49 conveniently secured to the machine-frame 50, and has secured to its other end a downwardly-projecting arm 51 which moves a link 52 forwardly to rock 50 a bail 53 about supporting studs 54, Fig. 3, secured to the sides of the machine-frame 50. The bail is moved against the tension of a return spring 55, and carries the upper ends 55 of the links 12, which pass through a slot 56 therein, to the other side of the fulcrum 14 of the sub-levers 13 (Fig. 5). If a key 10 is now depressed, it will swing one of the type-bars of the rear set to printing position. During this movement the link 12 60 moves up and down in the slot 56 and the stud 26 may move slightly forward in the slot 27.

To lock the secondary carriage 34 in either of two positions, to which it may 65 be moved, on the primary carriage 33,

there is provided a latch 57, pivotally supported at 58 on the secondary carriage 34, which may be actuated, against the tension of a spring 59, by a finger-piece 60 (Figs. 1 and 5). In moving the platen from 70 one type-set to another, the finger-piece 60 is first pressed to raise the latch 57 out of a notch 61. The carriage is then moved slightly in the direction desired. The operator may now let go of the finger-piece 60, 75 so that the latch 57 may slide on the end bar 62 of the primary carriage 33 until the platen approaches the end of its movement, when the latch rides up an incline 63, which leads to the notch 61. The platen is arrested 80 in its movement when the latch 57 strikes against a stop 64, which projects beyond the highest point of the cam 63.

When the platen is moved to its rear position, the latch 57 is effective to hold the 85 bail 53 against the tension of the spring 55. When the platen is moved from the Fig. 5 to the Fig. 2 position, the latch is first actuated as hereinbefore described, and then moved to its forward position, during which 90 time the spring 55 becomes effective to swing the bail to its forward position against a stop 64. Thus, the links 12 are shifted to connect the keys with the forward set of 95 type-bars.

From the foregoing, it will be understood that the connecting of the keys, with either type-set, is controlled by the secondary carriage; that the secondary carriage is effective to connect the keys with the rear set of 100 type-bars; and that the spring 55, which is under the control of the secondary carriage, is effective to connect the keys with the front set of type-bars. Also that, by means of the stops 64 on the primary carriage 33, 105 the platen, through the intermediary of the secondary carriage 34, may be accurately positioned relatively to each type-set without any special attention of the operator.

The platen 22 is mounted on the secondary carriage 34 for case-shifting movements. These movements may be limited by suitable stops (not shown), similar to those in the Underwood machine. The platen is shifted by a shift key 65, which, when depressed, 110 swings a shift key-lever 66 about a pivot 67 to move forwardly an arm 68, projecting upwardly from the key-lever 66. The arm 68 engages with a shift-frame 69, comprising two ends 70, pivoted on studs 71, secured to 115 the side walls of the machine-frame 50. The two ends of the shift-frame are secured to each other by a cross-rod or rail 72 and a tie-rod 73.

A second shift-frame 74 has a pivot 75, in 120 the nature of a rock shaft, to which side plates 76 of the shift-frame are secured. The side plates are also joined by a shift-rod 77. The shift-frame 74 is connected to the shift-frame 69 by one or more links 78. 125 130

Thus, when the shift-key 65 is depressed, both shift-frames are rocked to move the shift-rails 72 and 77 upwardly. A roller 79, secured to a platen-frame 80, supporting the platen, normally rides over one of the shift-rails 72 and 77, and is moved upwardly therewith to shift the platen-frame 80 to bring the platen 22 to its upper-case position. The platen-frame is carried by the secondary carriage 34 and is guided in its movement thereon by two arms 81, projecting forwardly from a rock shaft 82, to which they are secured. The forward ends of the arms 81 are pivotally connected to studs 83 on the platen-frame 80. To assist in guiding the platen in its case-shift movements, there is provided a pair of auxiliary links 84, each pivotally mounted on the secondary carriage at 85, and extending rearwardly to the platen-frame 80, to which they may be pivotally connected at 86 in any convenient manner. A suitable counterbalance spring (not shown) may be provided for the rock shaft 82, as in the Underwood machine.

From the foregoing, it will be understood that the platen may be moved in three directions. It may be moved in a vertical direction during case-shifting operations, and in two horizontal directions for letter-feeding movements and for rendering it effective with either type-set.

The platen, if moved from one type-set to another while it is in its upper-case position, would drop to its lower-case position, but the shift-rails 72 and 77 are provided with beveled edges, so that as the platen approaches the other type-set, the roller 79 will engage with the beveled edge and ride into its proper relation with its shift-rail, thus shifting the platen back to its upper-case position.

When the type-bars are mounted on a common fulcrum, usually a type-guide is used. I have provided a fixed type-guide 87 at the printing point for the front set of type-bars. The rear set of type-bars is provided with a type-guide 88, which is pivotally mounted on a sufficiently wide bearing 89 supported on suitable brackets 90, secured to a type-bar segment 91. This is done to move the type-guide 88 from its effective position (Fig. 5), to its ineffective position (Fig. 2), when the platen is moved from the rear to the front set of type-bars, so that the secondary carriage and platen meet with no obstruction when the platen is so moved.

During the forward movement of the secondary carriage and the platen 22, the upper end of the lever 47 moves forwardly, causing an arm 92, extending therefrom, to pull on a link 93 and swing the type-guide 88 about its pivot 89 from the Fig. 5 to the Fig. 2 position. It will be remembered

that the movement of the lever 47 is controlled by the rail 45 on the secondary carriage 34, and that the movement is effected by the spring 55. When the platen is moved from the Fig. 2 to the Fig. 5 position, the rail 45 engages during the latter part of such movement to swing the lever 47 rearwardly, as hereinbefore described. At the same time the arm 92 pushes on the link 93 to swing the type-guide 88 about its pivot 89 from the Fig. 2 to the Fig. 5 position. A suitable stop 94 may be provided to arrest the type-guide 88 in its effective position. This stop also steadies the guide and takes up any back thrust that may be imparted to the guide by the type-bars 18.

It will be seen that the rear type-guide is rendered effective simultaneously with the connecting of the keys to the rear set of type-bars.

The line-spacing mechanism for the platen may be similar to that of the Underwood machine and may include a line-spacing handle 95, pivotally supported on the secondary carriage at 96. The line-spacing handle 95 has projecting therefrom an arm 97, which, when the handle 95 is actuated, engages with a slide 98 to move the latter rearwardly on the platen-frame 80. A pawl 99, during this movement, engages with a ratchet wheel 100 secured to a platen-shaft 101, to rotate the platen 22.

An inking ribbon 102 is provided, which I have preferably shown as mounted on the secondary carriage 34, so that it may be moved with the platen to either type-set. The ribbon bears a fixed relation to the platen and is arranged in front of the platen between brackets, one at each side of the platen, and secured to the platen-frame 80.

The ribbon 102 may be fed from one to another of two spools 104, rotatably mounted on brackets 105, supported on the platen-frame 80. To feed the ribbon, there is secured to the platen-shaft 101 a gear-wheel 106, which moves with the platen during line-spacing operations, to drive a pinion 107, conveniently secured to one of the spools 104, thus winding the ribbon on one spool from the other. In the drawings, I have shown driving mechanism associated with one spool, but both spools may be provided with similar driving mechanism, and a ribbon-reversing mechanism may also be used, as shown in the McCormack patent, herein-referred to. It will be seen that the ribbon is positioned at such an angle in front of the platen so as to avoid obstructing the view of the writing line on the platen.

By an inspection of Fig. 3, it will be seen that the type-bars are arranged on a curved fulcrum rod and the bell-crank or intermediate levers 16 are arranged on a straight fulcrum rod. With this arrangement, the

upwardly-extending arms of the bell-crank 16, from the center to the end ones, increase in length. The forwardly-projecting arms, with which the sub-levers 13 engage, are 5 preferably all of the same length. As the distance of travel of the upper ends of the bell-crank forming the connections between the bell-crank and the type-bars is common to all of the bell-crank, it follows 10 that the angular movement of the bell-crank near the end is less than that of the center bell-crank. To compensate for this difference in angular movement and retain a uniform key depression of all of the keys 15 in a single bank, the key-levers may for this purpose be provided with individual fulcrums 108, which may be arranged at different distances away from the points of connection 25. These fulcrums may be conveniently supported on brackets 109 secured 20 to the machine-frame.

It will be seen that with this arrangement in which the platen is supported on the secondary carriage, which is movable 25 independently of the primary carriage, moving the platen from one type-set to another, certain other devices used in the Underwood machine, as, for example, the margin-stops and tabulating mechanism, may 30 coöperate with the primary carriage 33; thus, these devices will remain undisturbed while moving the platen from one type-set to another.

Variations may be resorted to within the 35 scope of the invention, and portions of the improvements may be used without others.

Having thus described my invention, I claim:

1. In a typewriting machine, the combination of a plurality of type-sets arranged in line; one back of another, said type-sets being mounted so that corresponding elements will have corresponding movements relative to the rest of the machine, a platen, mountings for said platen and said type-sets adapted to permit their relative movement to permit any of said type-sets, to print upon the platen and means, including keys, for actuating said 50 type-sets.

2. In a typewriting machine, the combination of a plurality of front-strike type-sets arranged one back of another, a single set of keys, a normally operative type-guide for one set, a normally inoperative type-guide for the other set, means for rendering said keys effective with any one of said type-sets, and means connected thereto to make the second guide operative 55 and inoperative.

3. In a typewriting machine, the combination of a plurality of sets of type-bars, means, including a single set of keys, for actuating said sets of type-bars, and a 60 platen mounted for movement from the

front to the back of the machine, and in a reverse direction, to render it effective with any one of said sets of type-bars.

4. In a typewriting machine, the combination with a plurality of sets of type-bars 70 and actuating means therefor, including a single set of keys, of a platen movable in a letter-feed direction, and means adapted to effect a relative movement between said platen and said sets of type-bars in a direction at right angles to the path of travel of said platen, to render said platen effective with any one of said sets of type-bars. 75

5. In a type writing machine, the combination of a plurality of type-sets arranged 80 one back of another, a single set of keys, a platen, and means adapted to effect a relative movement between said platen and said type-sets, to render said platen effective 85 with any one of said type-sets.

6. In a typewriting machine, the combination of a plurality of type-sets arranged 80 one back of another, a single set of keys, a platen movable into effective relation with any one of said type-sets, and means for 90 connecting said keys with any one of said type-sets.

7. In a typewriting machine, the combination of a plurality of type-sets arranged 95 one back of another, a single set of keys, a platen movable into effective relation with any one of said type-sets, a carriage for said platen, said carriage being movable to render said platen effective with any one of 100 said type-sets, and means controlled by said carriage for connecting the keys with the type-set to which the platen is moved.

8. In a typewriting machine, the combination of a plurality of sets of type-bars arranged one back of another, a single 105 platen mounted for movement to positions to be engaged by any one of said sets of type-bars, and means, including a single set of keys, for actuating any one of said sets of type-bars. 110

9. In a typewriting machine, the combination with two sets of type-bars, of sets of mechanisms for actuating said type-bars, each set of mechanism comprising a centrally pivoted sub-lever, a key lever and two 115 intermediate levers, arranged substantially in the same plane, said sub-lever having a one-way driving connection with each of said intermediate levers, and means for rendering said key lever effective with either 120 set of type-bars by changing the connections between said key lever and said sub-lever to give an active stroke to said sub-lever in one direction or the other.

10. In a typewriting machine, the combination of two sets of type-bars, sets of mechanisms for actuating said type-bars, each set of mechanism comprising a centrally pivoted sub-lever, a key lever, a link 125 and two intermediate levers, said sub-lever 130

having one-way driving connections at opposite ends with the respective intermediate levers, all of the parts of each set of mechanism being in substantially the same plane, 5 and means for shifting said links to change the connections between said sub-levers and said key levers.

11. In a typewriting machine, the combination of a plurality of type-sets arranged 10 one back of another, a platen, a single set of keys, means for permitting a relative movement between the type-sets and said platen to bring about an effective relation of the platen and any one of said type-sets, 15 and means to change the effective relation of said keys with said type-sets in accordance with the type-set between which and the platen an effective relation is established.

12. In a typewriting machine, the combination of two sets of type-bars, a set of 20 sub-levers having fixed fulcrums, two sets of intermediate levers having fixed fulcrums and adapted to connect the sub-levers to the type-bars, one set associated with each set 25 of type-bars, and means, including keys, for actuating said sub-levers in one direction to actuate one set of type-bars or in the opposite direction to actuate the other set of type-bars.

13. In a typewriting machine, the combination of two sets of type-bars, a single set of keys, a single set of sub-levers having connections for actuating either set of type-bars, each of said sub-levers having a single 35 fixed fulcrum, a set of links connecting said keys with said sub-levers, and means for shifting said links to engage on either side of said fulcrums.

14. In a typewriting machine, the combination of two sets of type-bars, a single set 40 of key levers, a single set of sub-levers, each of said sub-levers having a single fixed fulcrum, and means to actuate either set of type-bars, including connections between 45 said key levers and said sub-levers settable for positively swinging said sub-levers in clockwise or counter-clockwise directions in accordance with the type-bars to be actuated.

15. In a typewriting machine, the combination of a type-bar, and means for actuating said type-bar, said means comprising a bell crank, a centrally pivoted sub-lever engaging with said bell crank, said sub-lever having a slot therein, a key lever, and a link connecting said key lever with said sub-lever, said link engaging in the slot of said sub-lever and being movable therein to either side of the center of said sub-lever.

16. In a typewriting machine, the combination of two sets of type-bars, two sets of intermediate levers, one for each set of type-bars, and a set of sub-levers associated with said sets of intermediate levers, each 65 sub-lever being so disposed that one end

thereof will engage to actuate its associated intermediate lever while the other end moves idly away from its associated intermediate lever, said sub-levers being also reversely operable.

17. In a typewriting machine, the combination of two sets of type-bars, two sets of intermediate levers, one for each set of type-bars, a set of pivoted sub-levers, said sub-levers having slots therein, key levers, 70 links connecting said key levers with said sub-levers, and means for shifting said links in said slots, so that the sub-levers may be reversely actuated.

18. In a typewriting machine, the combination of type-bars, each type-bar having means for actuating it, said means comprising a bell-crank, a sub-lever, said sub-lever having a slot therein, a fulcrum for said sub-lever, a key-lever, and a link pivotally 80 connected to said key-lever, the slot in said sub-lever being substantially at right angles to the plane in which said fulcrums and the points of connection of the links with said key-levers lie, and means for moving one 85 end of said link in said slot.

19. In a typewriting machine, the combination of two sets of type-bars, each type-bar having a plurality of types thereon, means for actuating either set of type-bars, 90 said means comprising a single set of sub-levers, each of which is mounted for movement about a single fixed fulcrum, and a set of keys, and means for connecting said keys differently with said sub-levers so that the 100 latter may be differently moved to actuate either set of type-bars.

20. In a typewriting machine, the combination of two sets of type-bars, means for actuating said type-bars, said means comprising a single set of sub-levers having slots 105 therein, each of said sub-levers being mounted for movement about a single fixed fulcrum, key-levers, links connecting said key-levers with said sub-levers, and means for shifting said links in said slots so that the sub-levers may be reversely actuated by said key-levers.

21. In a typewriting machine, the combination of a type-bar, means for actuating 115 said type-bar, said means comprising an intermediate lever, a sub-lever engaging with said intermediate lever, said sub-lever being mounted for movement about a single fulcrum, a key lever, and a link connecting said key lever with said sub-lever, and means for shifting said link.

22. In a typewriting machine, the combination of a type-bar, means for actuating 125 said type-bar, said means comprising a bell crank, a sub-lever engaging with said bell crank, said sub-lever being mounted for movement about a single fulcrum, a key lever, and a link connecting said key lever with said sub-lever, said link being shiftable 130

relatively to the said sub-lever from one side to the other of said single fulcrum.

23. In a typewriting machine, the combination of a plurality of type-sets, a single set of keys, a primary carriage, a secondary carriage, and means controlled by said secondary carriage for connecting said keys with any one of said type-sets.

24. In a typewriting machine, the combination of two type-sets, a single set of keys, a primary carriage, a secondary carriage, a platen carried by said secondary carriage, said secondary carriage being movable at right angles to the path of travel of said primary carriage to bring the platen into coöperative relation with either one of said type-sets, and means engaged by said secondary carriage to disconnect said keys from one type-set and to connect them with the other type-set.

25. In a typewriting machine, the combination of a plurality of type-sets arranged one back of another, a single set of keys, a carriage, and means controlled by said carriage for connecting said keys with any one of said type-sets.

26. In a typewriting machine, the combination of a plurality of type-sets arranged one back of another, a platen in position to coöperate with one of said type-sets, and in advance of a position to coöperate with another type-set, a carriage adapted to move said platen to receive imprints from either type-set, a single set of keys, and means for automatically rendering said keys effective with any one of said type-sets according to the position of the platen.

27. In a typewriting machine, the combination with a carriage, of two sets of type-bars, sets of mechanisms for actuating said type-bars, each set of mechanism comprising a sub-lever and two intermediate levers arranged substantially in the same plane, a key lever, and means controlled from said carriage adapted to automatically disconnect said keys from one set of type-bars and connect them with the other set of type-bars.

28. In a typewriting machine, the combination with a plurality of type-sets, each including upper and lower-case characters, of a platen mounted for movement in one direction for letter-spacing, in a second direction for case-shift, and in a third direction to determine with which of said type-sets said platen shall coöperate.

29. In a typewriting machine, the combination with a plurality of type-sets, each having upper and lower-case characters, of a platen mounted for movement in one direction horizontally for letter-feeding, in another direction horizontally for determining with which of said type-sets said platen shall coöperate, and for movement vertically to change from one case to the other.

30. In a typewriting machine, the com-

bination of a plurality of type-sets, each set having a different kind of print and comprising upper and lower-case types, and a platen movable in a letter-feed direction and in two directions at right angles to the first mentioned direction for case-shifting and type-changing.

31. In a typewriting machine, the combination with a plurality of type-sets, and a separate set of independently-operable type-bars for each type-set, each of said type-sets including characters of a plurality of cases, of a carriage, a single escapement for said carriage, a platen, and means for moving said platen relatively to said carriage from one type-set to another with said carriage at rest.

32. In a typewriting machine, the combination with a plurality of type-sets, and a separate set of independently-operable type-bars for each type-set, each of said type-sets including characters of a plurality of cases, of a primary carriage and escapement therefor, a secondary carriage, and a platen supported by said secondary carriage, said secondary carriage being movable independently of said primary carriage, to render said platen effective with any one of said type-sets.

33. In a typewriting machine, the combination with a plurality of type-sets, and a separate set of independently-operable type-bars for each type-set, each of said type-sets including characters of a plurality of cases, of a primary carriage, a secondary carriage, and a platen supported by said secondary carriage, said secondary carriage being movable relatively to said primary carriage to render said platen effective with any one of said type-sets.

34. In a typewriting machine, the combination of a plurality of type-sets arranged one back of another, a primary carriage, an escapement therefor, a secondary carriage, and a platen supported by said secondary carriage, said carriages being adapted to be moved together during letter-feeding movements, and said secondary carriage being movable independently of said primary carriage to bring said platen into effective relation with any one of said type-sets.

35. In a typewriting machine, the combination with a plurality of type-sets, and a separate set of independently-operable type-bars for each type-set, each of said type-sets including characters of a plurality of cases, of a primary carriage, a secondary carriage, and a platen supported by said secondary carriage, said secondary carriage being movable at right angles to the path of travel of said primary carriage, to render the platen effective with any one of said type-sets.

36. In a typewriting machine, the combination of a primary carriage, a plurality of sets of type-bars, each of which carries

characters of a plurality of cases, a secondary carriage, and a rotatable platen supported to permit case-shift movement on said secondary carriage, said secondary carriage being movable independently and at right angles to the path of the travel of said primary carriage to selectively coöperate with any set of type-bars.

37. In a typewriting machine, the combination of type-bars, each of which carries characters of a plurality of cases, a primary carriage, an escapement for said carriage, a secondary carriage, and a rotatable platen supported on said secondary carriage for case-shift movement with respect thereto, the latter being movable independently and at right angles to the direction of movement of said primary carriage.

38. In a typewriting machine, the combination of type-bars, each of which carries characters of a plurality of cases, a primary carriage, an escapement therefor, a secondary carriage, and a rotatable platen supported on said secondary carriage for case-shift movement thereon, said carriages being adapted to move together during letter-feeding movements, and said secondary carriage being movable independently of said primary carriage.

39. In a typewriting machine, the combination of a plurality of type-sets, a platen, a carriage, a single set of keys, there being a relative shifting movement between said type-sets and said platen to render the platen effective with any one of said type-sets, and a single escapement for said carriage under the control of said keys.

40. In a typewriting machine, the combination with two sets of type-bars, of a carriage comprising a platen movable into effective relation with any one of said sets of type-bars, a single set of keys to actuate either set of type-bars, and an escapement for said carriage adapted to be actuated by any one of said sets of type-bars.

41. In a typewriting machine, the combination with a carriage, of two sets of type-bars arranged one back of another, a plurality of universal bars, one for each set of type-bars, and an escapement for said carriage adapted to be actuated by either one of said universal bars.

42. In a typewriting machine, the combination with a carriage, of a plurality of sets of type-bars, a single set of keys for said type-bars, an escapement for said carriage, and a floating frame adapted to be actuated by either set of type-bars to actuate said escapement.

43. In a typewriting machine, the combination with a carriage, of a plurality of sets of type-bars, an escapement for said carriage, and a floating frame comprising a plurality of universal bars, one for each set of type-bars.

44. In a typewriting machine, the combination of a plurality of type-sets arranged one back of another, each set comprising upper and lower-case types, a platen, means adapted to effect a relative movement between said platen and said type-sets to render the platen effective with any one of said type-sets, and case-shifting means which may be actuated when the platen is in effective relation with any one of said type-sets.

45. In a typewriting machine, the combination of a plurality of type-sets arranged one back of another, a platen, means for moving said platen into effective relation with any one of said type-sets, case-shifting means comprising a plurality of shift frames, and a key for actuating said shift frames to shift the platen when the latter is in effective relation with any one of said type-sets.

46. In a typewriting machine, the combination with a plurality of type-sets, of a primary carriage, a secondary carriage, and a platen supported by said secondary carriage, said secondary carriage being movable relatively to said primary carriage to render said platen effective with any one of said type-sets, said platen being supported for case-shifting movements on said secondary carriage.

47. In a typewriting machine, the combination of a plurality of type-sets, a primary carriage, a secondary carriage, a platen frame carried by said secondary carriage, a platen supported by said platen frame, said secondary carriage being movable relatively to said primary carriage, to bring the platen into effective relation with any one of said type-sets, and means for shifting said platen frame relatively to said secondary carriage, to effect case-shift movements of said platen.

48. In a typewriting machine, the combination of a plurality of type-sets arranged one back of another, each set having upper and lower-case types, a single set of keys for actuating said type-sets, case-shifting means, and a single platen with which said type-sets may coöperate.

49. In a typewriting machine, the combination of type-bars, each having thereon characters of a plurality of cases, a primary carriage, a secondary carriage, a platen supported by said secondary carriage for case-shift movement with respect thereto, said secondary carriage being movable relatively to said primary carriage, and means for locking said carriages together.

50. In a typewriting machine, the combination of type-bars, each having thereon characters of a plurality of cases, a primary carriage, a secondary carriage, a platen supported by said secondary carriage for case-shift movement with respect thereto, said secondary carriage being movable relatively to said primary carriage, means for locking

said carriages together, and releasing means for said locking means.

51. In a typewriting machine, the combination of a plurality of type-sets, each of which includes characters of a plurality of cases, a primary carriage, a secondary carriage, a platen supported on said secondary carriage, said secondary carriage being movable relatively to said primary carriage, to bring the platen into effective relation with any one of said type-sets, and means for locking said primary carriage to said secondary carriage.

52. In a type-bar typewriting machine, the combination with a plurality of type-sets, each of which includes characters of different cases, each set on its own set of separately-operable type-bars, of a primary carriage, a secondary carriage, a platen on said secondary carriage, said secondary carriage being movable relatively to said primary carriage to render the platen effective with either type-set, stops for limiting the movement of said secondary carriage when it is so moved, and means for locking said secondary carriage in its moved position.

53. In a typewriting machine, the combination with a platen mounted for forward and rearward movement, and a set of type-bars, of a type-guide, and means for moving said type-guide away from said platen upon forward movement, and for restoring said type-guide to normal position upon rearward movement of said platen.

54. In a typewriting machine, the combination with a platen and a set of type-bars, of a type-guide, a movable platen-support, and means, controlled by said platen-support, for moving said type-guide out of the path of said platen.

55. In a typewriting machine, the combination with a set of type-bars, of a device, including a platen, movable in a direction at right angles to letter-feeding movements thereof, a type-guide, and means, controlled by said device, for moving said type-guide out of the path of said platen.

56. In a typewriting machine, the combination with a set of type-bars, of a platen movable in a direction at right angles to letter-feeding movements thereof, a type-guide, and means rendered effective by movement of said platen for moving the type-guide out of the path of said platen.

57. In a typewriting machine, the combination with a set of type-bars, of a platen, a carriage for said platen, said platen being movable in a direction at right angles to letter-feeding movements thereof, a type-guide, and means for moving said type-guide out of the path of said platen, said means being controlled by said carriage.

58. In a typewriting machine, the combination with a platen and type-bars, of a type-guide, type-bar-actuating means, means

to render said actuating means effective or ineffective, and means for rendering said type-guide effective when said actuating means is effective.

59. In a typewriting machine, the combination with a platen and type-bars, of a type-guide, type-bar-actuating means settable to effective or ineffective condition, means for rendering said type-guide effective upon a setting of said type-bar-actuating means to effective condition, and a stop for said type-guide.

60. In a typewriting machine, the combination with a platen and type-bars, of a type-guide, said platen being adapted to move past said type-guide, and means for moving said type-guide to an effective position after the platen has been so moved.

61. In a typewriting machine, the combination with a platen and type-bars, of a pivoted type-guide, said platen being adapted to move past said type-guide, and means controlled by said platen for swinging said type-guide into an effective or ineffective position.

62. In a typewriting machine, the combination with a platen, of two sets of type-bars arranged one back of another, two type-guides, one for each set of type-bars, said platen being adapted to move from one set of type-bars to the other, the type-guide associated with the rear set of type-bars being normally ineffective and out of the path of the platen, and means adapted to move the last-mentioned type-guide to an effective position when the platen is moved to the rear set of type-bars.

63. In a typewriting machine, the combination with two type-sets, of a platen, two type-guides, one for each type-set, means adapted to effect a relative movement between said platen and said type-sets to render said platen effective with any one of said type-sets, and means for moving one of said type-guides to an unobstructable position.

64. In a typewriting machine, the combination with two sets of type-bars, of a platen, two type-guides, one for each set of type-bars, a single set of keys, means for moving said platen from one set of type-bars to another, and means adapted to change the connection of said keys relatively to said type-sets and to move said type-guide out of the path of said platen when the latter is thus being moved.

65. In a typewriting machine, the combination with two sets of type-bars arranged one back of another, of a platen, two type-guides, one for each set of type-bars, means for actuating said type-bars, means for moving said platen from one set of type-bars to another, and means for swinging one of said type-guides out of the path of said platen when the latter is moved from one set of type-bars to another.

66. In a typewriting machine, the combination with a set of type-bars, of a type-guide, a primary carriage, a secondary carriage, a platen on said secondary carriage, 5 the latter being movable at right angles to the path of travel of the primary carriage, and means controlled by said secondary carriage to move said type-guide out of the path of said secondary carriage.
- 10 67. In a typewriting machine, the combination with a plurality of type-sets and a carriage comprising a platen, of a plurality of type-guides, one for each type-set, and means controlled by said carriage for moving one of said type-guides away from said platen.
- 15 68. In a typewriting machine, the combination with a plurality of type-sets, of a primary carriage, a secondary carriage, a 20 platen, a plurality of type-guides, one for each type-set, one of said carriages being effective to move said platen into effective relation with any one of said type-sets, and means controlled by the carriage to move one 25 of said type-sets out of the path of said platen.
69. In a typewriting machine, the combination with two sets of type-bars, of a primary carriage, a secondary carriage, a 30 platen on said secondary carriage, a single set of keys, two type-guides, one for each set of type-bars, said secondary carriage being adapted to move said platen away from one set of type-bars and into effective relation 35 with the other set of type-bars, and means controlled by said secondary carriage for rendering the type-guide associated with the last-mentioned set of type-bars effective.
70. In a typewriting machine, the combination with a platen, of two type-sets, two type-guides, one for each type-set, a single set of keys, and means for simultaneously effecting the following operations, namely, 40 to move the platen to an effective relation with one of said type-sets, to move the type guide associated with the last-mentioned type-set to its effective position, and to connect the keys with the last-mentioned type-set.
- 45 71. In a typewriting machine, the combination with a plurality of type-sets, each type-set including upper and lower-case characters, and a platen, of a ribbon, and means for moving said ribbon bodily into 50 effective relation with any one of said type-sets.
72. In a typewriting machine, the combination with a platen, of a plurality of type-sets, each of which includes upper and 55 lower-case characters, a ribbon, and means for moving said platen and said ribbon into effective relation with any one of said type-sets.
- 60 73. In a typewriting machine, the combination with a platen, of a plurality of type-sets arranged one back of another, a primary carriage, a secondary carriage, a platen on said secondary carriage, 65 and means for moving said platen and said ribbon into effective relation with any one of said type-sets.
74. In a typewriting machine, the combination with a carriage comprising a platen, of a plurality of type-sets, each of which includes upper and lower-case characters, and a ribbon, said carriage being movable to bring said ribbon and said platen 70 into effective relation with any one of said type-sets.
- 75 75. In a typewriting machine, the combination with a carriage comprising a platen, of a plurality of type-sets, each of which includes upper and lower-case characters, and a ribbon, said ribbon being supported by said carriage and movable with said platen into effective relation with any one of said type-sets.
76. In a typewriting machine, the combination with types, of a main carriage, a supplementary carriage, a platen mounted for case-shift movement on said supplementary carriage, and a ribbon carried by said 80 supplementary carriage.
77. In a typewriting machine, the combination with types, of a main carriage, a supplementary carriage, a platen mounted on said supplementary carriage for case-shift movement with respect thereto, a ribbon carried by said supplementary carriage, 85 line-spacing mechanism for said platen, and ribbon-feeding mechanism controlled by said line-spacing mechanism.
78. In a typewriting machine, the combination with types, of a main carriage, a supplementary carriage, a platen mounted on said supplementary carriage for case-shift movement with respect thereto, a ribbon carried by said supplementary carriage, line-spacing mechanism for said platen, and ribbon-feeding mechanism controlled by 90 said line-spacing mechanism, said ribbon-feeding mechanism and said line-spacing mechanism being supported by said supplementary carriage.
79. In a typewriting machine, the combination with a plurality of type-sets, each having upper and lower-case characters, of 95 a primary carriage, a secondary carriage, a platen carried thereby and movable into effective relation with any one of said type-sets, and means carried by said secondary carriage for line-spacing said platen.
80. In a typewriting machine, the combination of a plurality of type-sets arranged one back of another, a primary carriage, a secondary carriage, a platen carried thereby, 100 said secondary carriage being adapted to be moved at right angles to the path of travel of said primary carriage to bring said platen into effective relation with any one 105
- 110
- 115
- 120
- 125

of said type-sets, and means carried by said secondary carriage for line-spacing said platen.

81. In a typewriting machine, the combination with a platen, of two type-sets, keys, two type-guides, one for each type-set, a single ribbon, and means for simultaneously effecting the following operations, namely, to move said ribbon and said platen from one type-set to another, to move the type-guide associated with the last-mentioned type-set to its effective position, and to connect the keys with the last-mentioned type-set.

82. The combination with a platen, of a plurality of sets of type-bars coöperating with said platen, each type-bar having a plurality of types thereon, a plurality of intermediate elements, each intermediate element being connected to a type-bar in each set, keys connected to actuate said intermediate elements, actuating means coöperative with said intermediate elements, means for shifting said coöperative means, so that the intermediate elements may be actuated differently by said keys to actuate the type-bars of any one of the different sets, and means for selecting any one of the types on each type-bar.

83. The combination with a platen, of a plurality of type-sets arranged in line, one back of another, each set comprising upper and lower case types, said type-sets being separated from each other, actuating means including key-levers in line in front, means to cause a relative movement between said type-sets and said platen to render either set effective with said platen, and a stop to limit said relative movement.

84. The combination with a platen, of a plurality of type-sets arranged in line, one back of another, each set comprising upper and lower case types, said type-sets being separated from each other, actuating means including key-levers in line in front, means to cause a relative movement between said type-sets and said platen to render either

set effective with said platen, a stop to limit said relative movement, and locking means to maintain effective relation between said platen and either set.

85. The combination with a platen, of a plurality of type-sets arranged in line, one back of another, so that one is normally out of reach of the platen to permit each to swing clear of the other, a single set of keys and key-levers in line in front, means whereby said platen and any one of said type-sets may be brought into effective relation, and means for effecting operative connection between said single set of keys and either of said type-sets.

86. The combination with a platen, of a plurality of type-sets arranged in line, one back of another, each comprising types of a plurality of cases, a single set of keys and key-levers in line in front, means whereby said platen and either of said type-sets may be brought into effective relation, and means for effecting operative connection between said single set of keys and either of said type-sets.

87. In a typewriting machine, the combination with a plurality of type-sets arranged in line, one back of another, of a single set of keys in front of the sets, key-actuated means for actuating any of said type-sets, mechanism tending to render said key-actuated means ineffective with respect to one of said type-sets, and effective with respect to another, and means including a carriage for controlling said mechanism.

88. In a typewriting machine, the combination of a plurality of type-sets arranged one back of another, a platen positioned to coöperate with one of said type-sets, and movable to the rear of the first position to coöperate with another type-set, a single set of keys, and means for rendering said keys effective with any one of said type-sets.
